UNITED STATES PATENT OFFICE.

THEODORE A. GARROW, OF LOS ANGELES, CALIFORNIA.

COMBINATION DRIER.

Application filed March 11, 1924. Serial No. 698,531.

To all whom it may concern:

Be it known that I, THEODORE A. GARROW, a citizen of the United States, residing at Los Angeles, in the county of Los Angeles, 5 State of California, have invented a new and useful Combination Drier, of which the following is a specification.

This invention relates to equipment for drying granular materials such as sand, 10 gravel and clays.

An important use of a device of this character is in the preparation of paving materials. A widely used and highly satisfactory paving material employs in its composition sand, clay, asphaltum and possibly gravel. In combining the granular materials with the asphaltum, it is quite essential that they be in perfectly dry state and for the purpose of drying these materials which may have previously been washed, large rotary drying machines are employed. Such machines generally consist of a tubular shell mounted substantially horizontally so that it will rotate on the axis thereof. Into the forward end of this shell the materials to be dried are delivered and hot gases are at the same time directed into the rearward end of the shell, these gases being brought into contact with the material as they churn within the shell and advance therealong toward the rearward end of the shell. A drier of this type is particularly suited to the drying of sand and gravel and operates very efficiently with such materials. The equipment, however, is not found entirely satisfactory for the drying of clays which, on becoming dried, form a very light dust which is very susceptible to being carried off by the blast of heated air as it travels from the shell.

I have found that by introducing the heated air at the forward end of the shell so that the direction of flow thereof will be the same as the movement of material through the drier, a very efficient drying action may be accomplished without the carrying off of large quantities of finely powdered clay through the exhaust system. In the standard form of equipment, the agitation of materials is greatest at the forward end of the drier, and it is at this point that the drying gases leave the drying chamber, thus carrying off damp clay dust from the forward end of the drier. In my device, 55 the clay is all carried through the drier and

that which is carried off with the air blast is perfectly dry and may be separated centrifugally or otherwise and used in the manufacture of paving material; whereas materials now carried off in the blast contain too much moisture to be usable in combination with hot asphalt.

The especial advantages and further objects of the invention will be made evident hereinafter.

Referring to the drawing which is for illustrative purposes only,

Fig. 1 is a partly sectional diagrammatic view of a drier embodying the features of my invention.

Fig. 2 is a section taken substantially upon a plane represented by the line 2—2 of Fig. 1.

As shown in the drawing, the invention employs a cylindrical shell 11 which is mounted upon bearings 12 and rotated through a gear 13 by driving means, not shown. The interior of the shell is equipped with vanes 15 which serve to pick up materials placed in the shell, as it rotates so that these materials will fall back through the space within the shell, which space is generally maintained at a high temperature by the introduction of hot gases thereinto. For the purpose of heating the interior of the shell 11, my invention employs a combustion chamber 17 equipped with a burner 18 situated at the forward end of the shell; and a combustion chamber 19 situated at the rearward end of the shell and having therein a burner 20, these combustion chambers having air valves 32. In the drawing, the combustion chambers are indicated in simple shell form but may be lined with brick or other refractory material as the occasion may demand. At the forward end of the shell is a housing 22 equipped with a charging opening 23 which leads to a chute 24, the lower end of which chute rests adjacent to the inner end of the combustion chamber 17 and slopes inwardly so as to deliver the material to be dried into the forward end of the shell 11. At the rearward end of the shell is placed a discharge housing 31 in which the combustion chamber 19 is mounted and which is equipped with an upwardly extending cap member 25 having a lateral outlet 26 which joins with a longitudinal pipe 27. This pipe 27 extends to the lateral outlet 28 of a cap mem-

ber 29, mounted on the forward housing 22, from which there upwardly extends a stack 30.

The drier shell 11 is arranged to be mounted at a slope downward from the forward end thereof to the rearward end so as to produce a movement of the materials being dried toward the discharge end of the shell. When rock, gravel or sand is being dried, the materials are fed into the shell through the charging opening 23 and a blast of heated combustion gases are directed by the burner 20 into the shell, thus producing a flow of heated gases in counter direction to that of the materials being dried. Where the drying operation is carried on in a slow rate of speed, and where the materials being dried are quite heavy and contain but little dust, the valves 35 and 48 may be opened and the valves 36, 37 and 38 shut, so that the spent gases may be drawn from the forward end of the shell by the draught produced in the stack 30. If a rapid drying action is desired, and where there is considerable dust carried off by the blast, a very strong blast of air may be produced within the shell by closing the valve 48 opening valves 35, 36 and 37, and using a blower 40, the air from the blower being directed through dust collectors.

When the apparatus is being employed for finely powdered materials such as clays, the combustion chamber 17 and the burner 18 are used, thus introducing hot gases into the forward end of the shell as indicated at 42, these gases traveling from the front to the rear of the shell, while the material being dried advances in the same direction. It will be recognized, that the materials at the forward end of the shell are brought into contact with the gases when these gases are at their highest temperature and a gradual cooling of the gases take place as they travel rearwardly in the shell and produce a drying action on the clay therein. The drying gases are preferably carried off from the shell through the cap member 25 by operation of the exhaust blower 40. When either burner is off, its valve 32 is shut.

Where the materials being dried are exceedingly light, the quantity picked up and carried off by the blast may be quite large. This quantity, however, is thoroughly dried, having passed entirely through the drier, and may be separated from the air blast by centrifugal separators, or other means, and conveyed to the asphalt mixers. In this manner, the entire production of the drier is utilized, there being no losses, as in the present process of drying fine materials.

I claim as my invention:

1. In a device of the character described, the combination of: a rotary tubular shell; means at the forward end of said shell for delivering a material thereinto; means at

the rearward end of said shell through which said material is discharged; means equipping said shell for use in drying light or heavy materials, consisting of means situated at each end of said shell for introducing hot gases at each end of said shell; and means at each end of said shell for drawing off gases from the interior of said shell.

2. In a device of the character described, the combination of: a rotary tubular shell; means at the forward end of said shell for delivering a material thereinto; means at the rearward end of said shell through which said material is discharged; and means equipping said shell for use in drying light or heavy materials, consisting of burners situated at each end of said shell for selectively producing a flow of gases through said shell from either end thereof.

3. In a device of the character described, the combination of: a rotary tubular shell; means at the forward end of said shell for delivering a material thereinto; means at the rearward end of said shell through which said material is discharged, means equipping said shell for use in drying light or heavy materials, consisting of means for selectively producing a flow of gases through said shell from either end thereof; and exhaust means at each end of said shell for drawing off gases from the interior of said shell.

4. In a device of the character described, the combination of: a rotary tubular shell; means at the forward end of said shell for delivering a material thereinto; means at the rearward end of said shell through which said material is discharged; and means equipping said shell for use in drying light or heavy materials, consisting of housings forming combustion chambers at each end of said shell, and burners situated in each of said housings for selectively producing a flow of gases through said shell from either end thereof.

5. In a device of the character described, the combination of: a rotary tubular shell; means at the forward end of said shell for delivering a material thereinto; means at the rearward end of said shell through which said material is discharged; and means equipping said shell for use in drying light materials, consisting of means for introducing hot gases into the forward end of said shell; and exhaust means for drawing off said gases from the rearward end of said shell.

6. In a device of the character described, the combination of: a rotary tubular shell; means at the forward end of said shell for delivering a material thereinto; means at the rearward end of said shell through which said material is discharged; and means equipping said shell for use in drying light materials, consisting of means for introducing hot gases into the forward end of said

shell; and exhaust means for drawing off said gases from the rearward end of said shell.

7. In a device of the character described, 5 the combination of: a rotary tubular shell; means at the forward end of said shell for delivering a material thereinto; means at the rearward end of said shell through which said material is discharged; means equipping said shell for use in drying light or heavy materials, consisting of means for introducing hot gases at each end of said shell; a draw off housing at each end of said shell; a pipe connecting between said housings; 10 exhaust means at one end of said pipe; and means controlling the flow of gases through said pipe.

8. In a device of the character described,

the combination of: a rotary tubular shell; means at the forward end of said shell for 20 delivering a material thereinto; means at the rearward end of said shell through which said material is discharged; means equipping said shell for use in drying light or heavy materials, consisting of means for 25 selectively producing a flow of gases through said shell from either end thereof; a draw off housing at each end of said shell; a pipe connecting between said housings; exhaust means at one end of said pipe; and means 30 controlling the flow of gases through said pipe.

In testimony whereof, I have hereunto set my hand at Los Angeles, California, this 21st day of February, 1923.

THEODORE A. GARROW.
